UNITED STATES PATENT OFFICE.

FRED C. DENNIS, OF BLAIR, OKLAHOMA.

AUTOMATIC GASOLINE-DISPENSING MACHINE.

1,347,147.

Specification of Letters Patent. Patented July 20, 1920.

Application filed September 27, 1917. Serial No. 193,541.

To all whom it may concern:

Be it known that I, FRED C. DENNIS, a citizen of the United States, residing at Blair, in the county of Jackson and State of Oklahoma, have invented certain new and useful Improvements in Automatic Gasoline-Dispensing Machines, of which the following is a specification.

This invention is an automatic gasoline machine and has for its principal object the production of a coin controlled mechanism which will dispense a predetermined amount of gasoline or other fuel to be received therefrom.

Another object of this invention is a production of an automatic gasoline machine wherein the coin inserted in the device will cause a valve to open for permitting gasoline to flow into a weighing tank and after a predetermined amount of gasoline passes into the tank, the flow of the gasoline into the tank will be stopped.

A further object of this invention is the production of an automatic gasoline machine wherein the coin control mechanism will automatically open a valve in the bottom of the weighing tank for permitting the gasoline to pass therefrom after the proper quantity of gasoline has been injected thereinto.

A still further object of this invention is a production of an automatic gasoline machine wherein the coin controlled mechanism will be automatically reset for another operation after dispensing a predetermined amount of gasoline.

With these and other objects in view this invention consists of certain novel combinations, constructions, and arrangement of parts, as will be hereinafter fully described and claimed.

One practical form of construction and assembly will be described and is illustrated in the drawings, in which—

Figure 1 is a central vertical section of the automatic gasoline machine.

Fig. 2 is a horizontal section taken on line 2—2 of Fig. 1, looking in the direction of the arrows, portions of the machine being removed.

Fig. 3 is a section taken on the line 3—3 of Fig. 1 looking in the direction of the arrows, portions of the machine not being shown.

Fig. 4 is a section taken on the line 4—4

of Fig. 1, looking in the direction of the arrows and,

Fig. 5 is a vertical section taken on the line 5—5 of Fig. 1 looking in the direction of the arrows, portions of the device being shown in elevation.

Fig. 6 is a fragmentary detail perspective view of a portion of the operating mechanism.

Referring to the drawings by numerals, it will be seen that the automatic gasoline machine comprises an outer casing 1 which of course may be of any suitable shape as illustrated in Figs. 2, 3 and 4, while the lower end of this casing 1 rests upon the base 2, being secured thereto by securing means 3. The cover 4 is secured, as shown at 5, upon the upper end of the casing 1, whereby access may be had to the interior of the machine, if desired.

The supply pipe 6 projects through the base 2 and extends to a point adjacent the top 4 as shown in Fig. 1. The upper end of the supply pipe 6 is provided with a goose neck 7, for purposes to be hereinafter set forth. The brackets 8 are provided with bases which are held in fixed position upon the casing 1. The brackets 8 are provided with clamps 11 held by securing means 12 upon the supply pipe 6 for holding the same in a fixed position within the casing 1.

The discharge funnel 13 has a nozzle 14 projecting through the casing as shown in Figs. 1 to 4 inclusive. The clamping band 15 engages the funnel 13 and has its ends secured to the casing 1 in any suitable manner and thereby holds the funnel 13 in a set position. Since the nozzle projects beyond the outer side of the casing, it is obvious that a hose may be applied thereto for conveying the gasoline dispensed by the machine to a desired point.

The tank 18 is positioned above the funnel 13 and is slidably mounted upon the supply pipe 6 by the bracket 19, this bracket 19 being secured to the weighing tank 18 and being slidably mounted upon the supply pipe 6 by a loose clamp 20. The cover 21 is carried upon the upper end of the weighing tank and is provided with ears 22 pivotally secured as indicated at 23 to the beam 24. The bracket 25 is secured as indicated at 26 to the casing 1 and is pivotally secured as shown at 28 to the beam 24. The weight 29 is slidably mounted upon the beam 20 and

as a consequence constitutes a balance for the weighing tank 18. It should be understood that when the weighing tank 18 is empty the weight 20 will hold the weighing tank in its highest position. When however the weighing tank 18 is filled, it will move to a lower position by suddenly overcoming the counter balancing effect of the weight 29. It will be noted that the neck 7 of the supply pipe 6 projects through the cover 21 of the weighing tank 18 and extends into this weighing tank as shown in Fig. 1.

When a customer desires a quantity of gasolene, he inserts a coin through the opening 30 formed in the casing 1 and the coin guide 31 registering with this opening 30 directs the coin downwardly in an edgewise manner, thus causing the coin to strike upon the trigger 32 positioned directly beneath the coin guide 31. The coin pocket 33 is carried below the guide 31 and constitutes a receiver for the coin after the same disengages the trigger 32. It will be noted that the pocket 33 has a slot 34 at one side thereof permitting the trigger 32 to project into the pocket 33. It should further be noted that the door 35 is hingedly secured as shown 36 to the casing 1 and constitutes a closure for the pocket 33. In order to prevent unauthorized access to this pocket there is provided any suitable form of a locking device as shown at 37.

The bracket 38 is fixedly secured as shown at 39 to the casing 1 and the depending portion 40 of the trigger 32 is pivotally secured thereto as shown at 41. In order to urge the trigger in one direction a coil spring 42 is connected at its ends to bracket 38 and the depending portion 40. The lower end of the depending portion 40 is provided with a head 43 for purposes to be hereinafter set forth. The shaft 44 is rotatably mounted upon the bracket 45 while the primary weight 46 is fixed upon one end of the shaft 44. The head 43 normally engages the weight 46 for holding the same in a set position as indicated in Fig. 1. When however, the trigger 32 is swung by a coil falling thereon it will swing the head away from the weight 46 for releasing the same. This primary weight 46 will then swing downwardly thereby allowing the valve cord 47 connected to the bar 48 carried by the weight 46 to become slack. This valve cord 47 passes around the pulley 49 carried upon a bracket 50 which is clamped upon the supply pipe 6, as indicated at 51. The valve cord 47 is then connected to a lever 52 extending from the rotary valve 53 carried within the valve casing 54. This valve casing 54 is carried by the supply pipe 6, as shown in Fig. 1. The coil spring 55 is also connected to the lever 52 and is supported by the flange 56 of the bracket 57, which is fixedly mounted, as indicated at 58 within

the casing 1. It is therefore obvious that as the primary weight 46 swings downwardly and the valve cord 47 becomes slack the coil spring 55 will swing the lever 52 in one direction, thereby opening the valve 53 for permitting a free passage through the supply pipe 6. At this time, the gasolene will pass through this pipe and into the weighing tank 18. The weighing tank 18 is provided with a depending neck 59 which carries the sleeve 60. The ball valve 61 is provided with a stem 62 depending therefrom and extending through the neck 59 into the sleeve 60 as shown in Fig. 1. The operating link 63 is connected to the stem 62 and the link 63 is normally urged downwardly at one end by the coil spring 64 secured thereto and carried by the sleeve 60. In this way it is obvious that the ball valve may be held against accidental movement, while the weighing tank 18 is being filled. After the weighing tank 18 is nearly filled with gasolene flowing from the neck 7 the tank suddenly moves downwardly, thus swinging one end of the beam 24 upwardly. The end of the beam which is thus swung upwardly projects through the slotted bracket 65 fixedly secured, as indicated at 66, to the casing 1 adjacent the upper end thereof. The flexible strand 67 is secured to the last-mentioned end of the beam 24 and passes through the bar 48 mounted upon the primary weight 46 and carries the nut 68. Therefore, as the end of the beam 24 moves upwardly it will draw upon the last mentioned strand 67 and thus swing the weight 46 upwardly, thus causing the weight to draw upon the valve cord 47 for swinging the lever 52 against the tension of the spring 55 thereby closing the valve 53 and the flow of gasolene into the weighing tank will be automatically shut off.

When the weight 46 is swung upwardly in the manner hereinbefore specified the finger 69 carried by the weight 46 will be swung into engagement with the tripping arm 70. This tripping arm 70 is pivotally supported as shown at 71 upon the bracket 57. This tripping arm 70 is also provided with a latch head 72 which is normally held in engagement with the auxiliary weight 73 by the coil spring 74.

The auxiliary weight 73 is pivotally mounted upon the shaft 44 and is connected by the cord 75 to the bar 48 of the weight 46. This cord 75 passes over the pulley 76 mounted upon the bracket 38 and it is therefore obvious that when the primary weight 46 swings to a lower position it will draw the auxiliary weight upwardly as it is intended to have the primary weight weigh slightly more than the auxiliary weight. The bracket 77 is fixedly mounted upon the weight 73 and is provided with a slot 78 adjacent its lower end. The link 63 is piv-

totally supported by the bracket 79 carried within the casing 1 and this link projects through the slot 78 in the bracket 77. As the auxiliary weight moves the bracket 77 downwardly the bracket will swing the link 63, thereby causing the stem 62 to lift the ball valve 61 from its seat. The gasoline within the weighing tank 18 will then pass therefrom through the neck and the sleeve 10 to be dispensed into the funnel 13 and be finally passed from the casing 1. It should further be understood that as the weight swings downwardly the finger 80 will swing upwardly. The tightening cord 81 is attached to the finger 80 and passes through the guide eye 82. This tightening cord 81 is also provided with an eye 83 through which the valve cord 47 extends as shown in Fig. 1. It is therefore obvious that as 20 the finger 80 is swung upwardly it will draw upon the tightening cord 81 to further tighten the cord 47 for positively holding the valve in a closed position.

The weight 29 on the beam 24 will move 25 the tank 18 upwardly when sufficient gasoline has been discharged from the tank so as to allow the weight 27 to counter-balance same. This will cause the flexible strand 67 to permit the primary weight 46 to then have 30 a free engagement with the head 43. When another coin is inserted in the machine to cause the primary weight to again move downwardly, the cord 75 will immediately move the auxiliary weight 73 upwardly 35 thereby causing the weight 73 to permit the ball valve to return to its seat for retaining the gasoline injected into the weighing tank for a predetermined time.

The operation of the machine may be repeated as often as coins are inserted into the coin slot. It will be seen by referring to the foregoing description that as one weight is lowered the other weight is raised. It will further be noted that as the primary weight 45 is lowered the auxiliary weight is raised, and the valve operated by the auxiliary weight will be moved to a closed position, while the valve operated by the primary weight will be opened thereby permitting 50 gasoline to be injected into the weighing tank and be held against displacement at the time this action is taking place. After the tank is filled, however, the primary weight will be finally raised to an elevated 55 position for cutting off the flow of gasoline, and the auxiliary weight will be lowered for opening the valve in the bottom of the tank for permitting the gasoline measured thereby to be dispensed therefrom.

From the foregoing description it will be 60 obvious that a very efficient self measuring machine has been provided, wherein after a coin has been inserted therein a proper quantity of gasoline may be measured and then 65 be dispensed although while the dispensing

action is taking place the supply of liquid fuel to the weighing tank will be cut off.

It is of course obvious that in many minor details changes may be made in the construction of this invention, such for instance, as 70 the manner in which the various brackets are employed for supporting the different pivoted elements without departing from the spirit of the invention and for this reason it is not intended to limit the construction of 75 this self measuring machine to the specific form herein shown, as it is intended to include all such forms of the device as properly come within the scope of the invention as claimed.

What I claim is:—

1. In a device of the class described, the combination of a casing having a fuel supply pipe, including a valve, yieldable means for turning the valve in one direction, a weight 85 pivotally mounted within said casing, a flexible cable connected to said weight and said valve, a trip lever having a head normally holding said weight in a set position, said lever adapted to be engaged by a coin 90 and thereby shifted to release the weight, whereupon the weight will release said cable to allow said valve to be operated, and means for returning said weight to its normal position, whereupon said cable will move the 95 valve to a closed position.

2. In a device of the class described, the combination of a casing having a fuel supply pipe including a valve, yieldable means for turning the valve in one direction, a 100 weighing tank movably mounted in said casing and provided with a beam, a strand depending from said beam, a weight pivotally mounted within said casing and provided with a connection engaging said strand, a 105 yieldable table connected to said weight and said valve, whereby the valve will be normally held in a closed position, means for normally holding said weight in a set position, said means adapted to be tripped by a 110 coin, thus releasing the weight, whereupon the cable will be flattened to allow said yieldable means to open the valve, and means for returning the weight to its normal position, thus causing the weight to draw upon said 115 cable and turn off the valve when said strand is moved by said beam and beam.

3. In a device of the class described, the combination of a casing having a supply pipe, a weighing tank movably mounted 120 within the casing and valve means carried by said tank, a link extending from said valve means, a weight having a bracket connected to said link, of means for automatically opening the supply pipe to allow liquid to pass into said tank until a predetermined amount of liquid has passed thereinto, whereupon the means will be returned to its normal position and release said weight, thus causing the weight to shift the bracket 125 130

and move the link to open the valve in said tank.

4. In a device of the class described, the combination of a casing, a supply pipe carried within said casing and having a valve, means for normally turning the valve in one direction, a tank movably mounted within said casing, a primary weight mounted within said casing, a coin trip carried within 10 said casing for engaging and normally holding the primary weight in a set condition, a flexible cable connected to the primary weight and said valve for normally holding the valve in a closed condition, a valve carried by said tank and having a link extending therefrom, an auxiliary weight pivotally supported in said casing and having a bracket engaging said link, a latch engaging said auxiliary weight for holding the same 15 in a set position, means carried by said primary weight to engage said last-mentioned latch when the primary weight is swung in 20

one direction to release said auxiliary weight, a beam having means connected to said primary weight, said beam being connected to said tank for returning said primary weight to its normal position, said primary weight being released by said coin trip, thus releasing the valve to allow liquid to flow into said tank until a predetermined 30 amount has been injected thereinto, whereupon said primary weight will be returned to its normal position to engage the latch of the auxiliary weight, thus allowing the auxiliary weight to move, whereupon the bracket thereof will move the link to open the valve in said tank.

In testimony whereof I affix my signature in presence of two witnesses.

FRED C. DENNIS.
